UNITED STATES PATENT OFFICE.

JOHN REID, OF NEW YORK, N. Y.

OIL-BURNING-FURNACE FRONT.

1,414,208.

Specification of Letters Patent. Patented Apr. 25, 1922.

Application filed April 9, 1920. Serial No. 372,714.

To all whom it may concern:

Be it known that I, JOHN REID, a subject of the King of Great Britain, and residing at 30 Church St., in the city of New York, in the State of New York, in the United States of America, have invented a new and useful Oil-Burning-Furnace Front, of which the following is the specification.

The invention relates to oil burning furnace fronts as described in the present specification and illustrated in the accompanying drawings that form part of the same.

The invention consists essentially in the novel means employed in directing the air whereby the front is made susceptible to natural draft as well as forced draft, which is peculiarly effective in the early condition of the fire.

The objects of the invention are to efficiently direct the air to the fire or to the flame in an oil burning furnace front so that the flow will have no dampening effect on the blaze no matter whether it is forced draft or natural draft; to construct a front for furnaces in which the parts are so made and assembled that they can be readily replaced, repaired and reassembled; to insure ready access to the interior of the furnace; and generally to provide a durable and serviceable furnace front that may under certain circumstances be so rearranged as to be temporarily or even permanently fitted up for a coal burning furnace without removing the main parts from the furnace mouth.

In the drawings, Figure 1 is a front elevation of the back plate with the intermediate walls in section as arranged in one form of my invention.

Figure 2 is a vertical sectional view of the form of invention illustrated in Figure 1.

Figure 3 is a front elevation of a back plate showing another arrangement of intermediate walls in section.

Figure 4 is a vertical sectional view of the form of invention illustrated in Figure 3.

Figure 5 is an elevation of the front plate applicable to either of the aforesaid forms of the invention.

Figure 6 is a sectional view of a modified arrangement of the parts.

Figure 7 is a perspective detail of the closure for natural draft doors.

Figure 8 is a perspective detail of a form of catch for the natural draft door.

In this invention the purpose is largely to combine natural draft and forced draft

effects in the one furnace front, though primarily the natural draft effects have the most prominence in the specification and drawings belonging to this application. However it is of first importance to start a fire with the mild effects of a natural draft and as the heat increases and becomes extreme then the benefit of the forced draft is very material to the efficient steaming properties of the furnace and this invention has to do with the arrangements of doors and plates whereby the direction of the air is so guided as to reach the furnace and more particularly the flame beyond the area surrounding the burner mouth.

Referring to the drawings, the back plate 1 is formed with the converging wall 2 surrounding the flame opening 3 which forms a cone shaped recess from the firebox side. The end of the cone recess wall 2 being offset vertically and secured in the thickened ring 4 preferably in grid form and filled with refractory material and corresponding to a Venturi tube. The lining plates 5 and 6 also terminate in the ring 4 and form air chambers both for cooling the lining and for supplying superheated air to the flame through the port 7, the air reaching the lining air chambers through the ports 8 in the back plate 1.

The air shield wall 9 in Figure 1 is shown at the top with the central port 10 closed by the valve 11, while the flare wall 12 at the lower portion of the front reaches up part way towards meeting the shield wall 9.

The front plate 13 is secured to the shield wall 9 and flare wall 12 and is formed with the upper draft door 14 and lower draft door 15.

The baffle plate 16 extends inwardly towards the back plate 1 from below the opening closed by the upper draft door 14 and terminates about midway between front and back plates.

The air cover 17 extends from the opening 18 in the front plate to the back plate immediately above the cone recess wall 2 and under the ledge 19 and is formed with the air port 20 situated under the baffle plate 16 thereby imparting a twist to the flow of air, which has the effect of avoiding pockets of dead air often occurring in furnace draft arrangements.

The cover plate 21 closes in the front opening 18 of the front plate 13 and is formed with the hinge draft door 22 in its upper

portion, the lower portion carrying the oil pipe sleeve 23 which supports the oil pipe and the burner 24 at its inner end, the said burner 24 being well retired between the 5 front plate in view of the cone recess wall 2 from the back plate.

The opening 18 in the front plate is slightly higher than the flame opening 3 in the back plate bringing the lower part of 10 the opening 18 opposite the flame opening 3, therefore a splendid draft effect can be obtained through the draft door in the closure plate 21.

The deflector shell 25 is mounted on the 15 oil pipe sleeve 23 and the vanes 26 project from the shell 25 into proximity with the ring 4 and are enclosed by the cylinder 27.

It will be seen that the deflector shell 25 is open at the end thereof adjacent to the 20 closure plate so that the air can flow inside said shell towards the flame from the burner 24, the burner mouth being protected by the bell mouth deflector 28 mounted on the oil pipe sleeve 23.

25 For natural draft effects, in this particular form of the invention, so soon as the fire gets a reasonable start and requires building up, the draft doors are gradually opened, until it is able to stand all the air that will naturally rush in to fill up the vacuum created.

This air through the upper draft door comes first in contact with the baffle plate and then flows through the port therebelow.

The air through the draft door in the closure plate flows between the outer cylinder 35 27 and the deflector shell 25 and through the deflector shell itself and is then deflected by the bell mouth deflector 28 and the ring 4, finally reaching the flame well clear of 40 the burner mouth.

Once the flame is well built up, that is to say, has reached the proper stage of combustion, then it is possible to turn on the forced draft through the valve and the great force 45 of air in its flow finds its way partly through the port 10 and partly beyond the ends of the shield wall 9, and if the natural draft doors are all closed, it flows steadily around, until it reaches all sides of the air register 50 formed by the deflector shell 25 the vanes 26 and the outer cylinder 27.

In Figures 3 and 4 the intermediate wall is shown as similar to many types of the Reid furnaces, in which the shield wall 29 55 is intermediate of the distance from the air register to the top of the front and is formed with the central port 30, closed by the valve 31, and the sloping sections 32 merging into the vertical sections 33 terminating in the inturned ends 34. The valves 35 close the ports between the flare 36 and the lower ends of the vertical section 33.

The flare wall 36 and the shield wall 29 are secured through the lugs 37 and 38 60 respectively to the front plate 39 and back

plate 40, the former having a central opening flanged by the outwardly projecting ring 41, and the latter having the flame opening 42 surrounded by the inwardly projecting annular wall 43.

70 The spider 44 is secured by the bolts 45 to the ring 41 and the cone deflector 46 is secured to the spider 44, while the oil pipe sleeve 47 is supported in the hub of the spider 44 and supports at the end of the oil pipe therein the burner 48.

The burner 48 is considerably retired towards the front plate from the flame opening and is within the end of the cone deflector 46, but the bell mouth deflector 49 is adjustably secured on the sleeve 47 and protects the burner mouth.

80 The closure plate 50 is adjustably mounted on the oil pipe sleeve 47 and carries a deflector cone 51 with it, so that when the closure plate 50 is moved along on the sleeve to allow natural draft thereto, the air is deflected by the cone 51 into and through the shell of the cone deflector 46, part of the flow 85 of course going through the vanes of the said cone deflector 46 on the outer side of the shell.

90 It will be readily seen that for forced draft effects this form of the invention is equally efficient with the other types of the Reid furnace fronts but the natural draft effects are prominently identified with this type and as explained in the foregoing, these are extremely useful particularly in building up the flame.

100 In Figures 5, 6, 7 and 8, a front is shown, which is particularly suitable for the natural draft effects and this front the annular wall 52 from the back plate 53 and surrounding the flame opening 54 extends quite a long 105 distance towards the front plate, so far indeed as to partially enclose the cone deflector 55 extending from the front plate.

The burner 56 is supported in the oil pipe sleeve 57 and the latter carries the inner bell mouth deflector 58.

The oil pipe sleeve 57 is supported by the bar 59, which is suitably bossed at 60 around the sleeve hole.

The bar 59 is formed with the hinge lugs 61 and 62, in which the straps 63 extend upwardly therefrom and the hinge straps 64 extend downwardly therefrom, each set of straps being independently pivoted in the said lugs.

115 The flap 65 is secured to the top hinge straps and the larger flap 66 is secured to the hinge straps 64.

The front plate 67 is formed with a large opening which is here shown as rectangular, 120 though it may be any shape and this opening is recessed therearound at 68 to form a seat for the flaps 65 and 66.

125 The bar 59 is secured to the inner side of the front plate 67, so that the burner 56 130

may be centrally arranged in the cone deflector 55 and this bar 59 extends across the opening in the said front plate and the flaps 65 and 66 open outwardly and in closing fit 5 into the seat 68. Any suitable form of opening and closing device may be used for this purpose, a ratchet 69 is illustrated engaged by the dog 70.

The lower draft door 71 is shown as attached to the front plate 67 and closes a corresponding opening near the bottom of the said front plate just above the flare wall 72.

The shield wall 73 is shown at the top, and side valves are arranged between said 15 flare wall and said shield wall and in the central port of the said shield wall.

These features are common to several of the Reid fronts and have been fully described in this specification.

20 The burner is retired towards the front plate from the flame opening in the same manner as already described.

In the operation of this form of the front for natural draft, the flap doors are opened 25 and as the lower door is much larger than the upper door a greater volume of air will flow in from below, which is correct, and to increase this volume of air the lower draft door in the front may also be opened.

30 Just as soon as the flame reaches that point of combustion, which may be considered as extreme heat, the forced draft may then be resorted to and the fire continued as herein before explained.

35 Many changes may be made in regard to the detailed construction without departing from the spirit of the invention and so long as these changes are within the scope of the claims for novelty following the protection accorded shall not be invalidated.

40 What I claim is:—

1. A furnace front comprising a front and back plate with intermediate walls forming an air pocket and an air director in 45 the central area of said pocket and surrounding a burner, said back plate having an annular wall encircling the flame opening and projecting towards the front plate, and said air director extending from said front 50 plate within said annular wall.

2. A furnace front comprising a front and a back plate with intermediate walls forming an air pocket and an air director in the central area of said pocket and sur- 55 rounding a burner, said back plate having an annular wall projecting towards the

front plate and surrounding the flame opening, and said air director having a plurality of curved vanes mounted on a converging casing extending from the front 60 plate to within said annular wall.

3. A furnace front comprising a front plate having an intermediate opening there-through, and an outward extending flange surrounding said opening, a closure for said 65 opening having a central cone deflecting member secured thereto, an oil pipe sleeve extending through said closure and through said cone deflector, a burner at the end of said sleeve, a bell mouthed deflector mounted 70 on said sleeve around said burner, a cone deflector having vanes projecting therefrom and extending inwardly and encircling said burner, a back plate having a flame opening and intermediate walls between said 75 front and back plates forming therewith an air pocket.

4. A furnace front comprising a front plate having an intermediate opening there-through, and a flange extending outwardly 80 from said opening, a closure for said opening having a deflecting member secured to the inside for natural draft effects, a spider rigidly secured to said flange, an oil pipe sleeve secured in said spider, a burner at 85 the inner end of said sleeve, a cone deflector having vanes projecting therefrom and surrounding said burner, a back plate having a flame opening and an inwardly projecting annular wall surrounding said flame 90 opening and intermediate walls forming with said front plate and said back plate an air pocket.

5. A furnace front comprising a front plate, back plate and intermediate walls 95 for an air pocket having an opening thereinto through the front plate and therefrom through the back plate, an air director between said front and back plates, a burner, a closure frame secured around the front 100 opening, a cross bar secured to said frame above the vertical centre thereof and having a central boss for supporting the burner tube, an upper door hinged to said bar, a lower door hinged to said bar and of greater 105 depth than said upper door and means for holding said doors close or open.

Signed at the city of New York, in the State of New York, in the United States of America, this 2nd day of April, 1920.

JOHN REID.
